UNITED STATES PATENT OFFICE.

CHESTER C. HOWE, OF NEW KENSINGTON, PENNSYLVANIA.

WASHING MACHINE.

Application filed September 23, 1922. Serial No. 590,005.

To all whom it may concern:

Be it known that I, CHESTER C. HOWE, a citizen of the United States, residing at New Kensington, in the county of Westmoreland, 5 State of Pennsylvania, have invented certain new and useful Improvements in Washing Machines, of which the following is a specification.

This invention is for an improvement in 10 brush washing machines and relates particularly to a tension adjustment for the scrubbing roll of such machines.

In brush washing machines, the clothes are held against a rapidly revolving brush by 15 means of a scrubbing roll which is yieldably urged toward the brush. For different kinds of clothes, it is desirable to be able to vary the tension of the scrubbing rolls so that where thick and thin pieces are being washed, some pieces will not be held 20 too firmly against the brush while others are not held sufficiently tight against the brush.

The present invention has for its principal object to provide a roll mounting and 25 spring adjustment for the roll which is more simple and efficient than other devices for this purpose now in use.

The invention may be readily understood 30 by reference to the accompanying drawings, in which:

Fig. 1 is a front elevation of a part of a brush washing machine embodying my invention;

Fig. 2 is an end elevation of the part of 35 the machine shown in Fig. 1;

Fig. 3 is a section on line III—III of Fig. 2;

Fig. 4 is a section on line IV—IV of Fig. 2.

40 In the drawings, 5 designates end frame plates of a brush washing machine, and 6 is a power driven brush rotatably carried between said plates in bearing 7. On each of the end plates 5, near the top thereof, is a lug 5^a from which a link 8 is pivotally suspended by means of a suitable bolt 9. A spring 9^a is carried on the bolt between the link and a nut 9^b on the bolt which urges the link against the lug. The lower end 45 portion of each of the links 8 has a bearing 10 therein, forming journals for supporting the opposite ends of a roller carrying shaft 12.

50 These bearings are so constructed as to 55 allow the shaft considerable freedom of

movement therein, the construction being shown in Fig. 4, from which it will be seen that the end of the shaft passes through a hole which is larger at its ends than at its center, so that the shaft may assume different angular positions in the link. Loosely carried on the shaft 12 is a scrubbing roller 11. Cotter pins 13 hold the shaft against endwise movement.

The springs 9^a prevent the roller from 60 bumping or jumping toward and away from the brush and from chattering when an article is being washed between the brush and the roller. I have found that without the springs, the scrubbing action is far inferior and that they are practically essential for the operation of the brush washer. The links are preferably of sufficient length to cause the center line of the roller to be 65 slightly below that of the brush.

Formed in the links, intermediate the 70 ends thereof, are a plurality of recesses or notches 14. Mounted on each link is a tensioning member 15 having a slot 16 therein through which the link passes. At one 75 end of the member 15 is a handle portion or grip 17, and a finger hole 18 may be provided. Connected to the other end of each member 15 is one end of a coil tension spring 19, the other ends of the springs being secured to lugs 20 in their respective plates 5.

The springs exert a pull on members 15 to yieldably urge the links, and consequently roller 11, against the rotary brush. By 80 adjusting members 15 to cause the metal at the end of slot 16 to enter one of the recesses or notches 14 in the links, the members 15 may be adjustably retained in position. When the members 15 are near the lower 85 end of links 8, the scrubbing roller 11 is held more tightly against the brush than when the members 15 are at the upper ends of the links, due to greater tension of the springs when members 15 are near the lower ends 90 and the increased leverage through which they exert their pull.

To change the pressure of the roll against the brush, the operator grasps the two members 15 and pulls toward him until the ends of slot 16 disengage the notches or recesses 14. The operator then moves members 15 up or down on the link, and lets them engage suitable notches 14 when he gets them to the desired position. In this way, the 100 105 110

pressure of the roll against the brush can be easily varied by the operator, according to the nature of the clothes to be scrubbed.

What I claim is:

- 5 1. A brush washer comprising a supporting frame, a rotary brush carried by the frame, a scrubbing roll for cooperation therewith, links at each end of the scrubbing roll pivotally connected with said frame for movably supporting the scrubbing roll, springs secured to the frame at each end of the brush, and means on said links movable longitudinally thereof, to which said springs connect, to yieldably hold the scrubbing roll against the brush, the pressure with which the roll engages the brush being varied by changing the position of said longitudinally movable means on the links.
- 10 2. A brush washer comprising a supporting frame, a rotary brush carried thereby, a scrubbing roll for cooperation therewith, links at each end of the scrubbing roll pivotally connected with said frame for movably supporting the scrubbing roll, springs cooperating with the links for yieldably holding the roll against the brush, and means carried by the links for varying the effective action of the springs.
- 15 3. A brush washer comprising a supporting frame, a rotary brush mounted therein, a link pivotally suspended from the frame

at each end of the brush, a roller carried by said links, each of said links having a notched portion thereon, a tensioning member slidably carried on the notched portion of each link and adapted to cooperate with the notches therein, and springs connecting said tensioning members with the frame, movement of said tensioning members on the links being utilized to vary the effective strength of said springs.

4. A brush washer comprising a frame, a rotary brush carried thereby, a link pivotally suspended from said frame at each end of the brush, a scrubbing roller carried by the lower ends of the links, and springs secured to the frame adjustably connected with said links intermediate the pivots therefor and the roller.

5. A brush washer comprising a supporting frame, a rotary brush carried thereby, a scrubbing roll for cooperation therewith, a link at each end of the supporting roll pivotally connected with the frame, means for yieldably holding the roll against the brush, and means engaging the upper end of the links for overcoming the tendency of the roll to jump toward and away from the brush.

In testimony whereof I affix my signature.

CHESTER C. HOWE.
